(57) **CLAIM**

The ornamental design for a golf support stick, as shown and described.

DESCRIPTION

FIG. 1 is an isolated perspective view of the golf support stick, showing the new design;

FIG. 2 is front elevational view of golf support stick thereof;

FIG. 3 is a rear elevational view of the golf support stick thereof;

FIG. 4 is a left side elevational view of the golf support stick thereof;

FIG. 5 is a right side elevational view of the golf support stick thereof;

FIG. 6 is a top plan view of the golf support stick thereof, FIG. 7 is a bottom plan view of the golf support stick thereof, FIG. 8 is an environmental perspective view of the golf support stick thereof; and,

FIG. 9 is an environmental perspective view of the golf support stick thereof.

The broken lines illustrate environmental subject matter that form no part of the claimed design.

1 Claim, 6 Drawing Sheets
